UNITED STATES PATENT OFFICE.

FRANK DUPUIS, OF PAWTUCKET, FREDERICK E. PAGE, OF PROVIDENCE, AND GEORGE H. PAGE, OF PAWTUCKET, RHODE ISLAND.

WATER-HEATING APPARATUS

No. 889,775.

Specification of Letters Patent.

Patented June 2, 1908.

Application filed June 24, 1907. Serial No. 380,834.

To all whom it may concern:

Be it known that we, FRANK DUPUIS, residing in the city of Pawtucket, in the county of Providence, FREDERICK E. PAGE, residing in the city of Providence, in said county, and GEORGE H. PAGE, residing in the city of Pawtucket, in said county, State of Rhode Island, citizens of the United States, have invented certain new and useful Improvements in Water-Heating Apparatus, of which the following is a specification.

The object of our invention is to combine the usual city water system of a building with the usual heating apparatus of said building, by means of the interposed device hereinafter specified and thus to provide hot water for culinary, domestic and other household uses, and with this object in view our invention consists of the novel construction, combination and arrangement of parts, as hereinafter described and claimed.

Like reference numerals indicate like parts.

Figure 1 is a view, partly in front elevation and partly in central longitudinal vertical section of our improved water-heating apparatus. Fig. 2 is a cross sectional view, as seen on line x—x. of Fig. 1. Fig. 3 is a view, in front elevation, on a small scale, of said apparatus, together with a hot water tank, and the pipes connected with the same. Figs. 4 and 5 are illustrations of an electric water-heating apparatus made in accordance with our invention.

In the drawings 1 represents a cylinder, cast of any suitable metal, and made with one end closed and one end open. The open end is internally threaded, and a cap 2, having screw-threads on its edge, fits in said open end. The closed end of the cylinder is tapped, as shown at 3, and the cap 2 is tapped, as shown at 4. The cylinder 1, near its open end, is tapped in two places, one on top shown at 5 and one at the bottom, shown at 6.

A steam pipe 7 leads from a steam-heater, or hot-water-heater, or hot-air-furnace, in the cellar, or some part of the building, and has a valve 8. An inlet pipe 9 leads from the valve 8 into the cylinder 1 through the nipple or tap 3.

50 A return pipe 10, connected with the cylinder through the nipple or tap 6, enters a valve 11, and a pipe 12 leads from the valve 11 to the radiator or heating system of the building.

55 A hot water tank 13 is of usual or any

preferred construction, and is illustrated in Fig. 3. A pipe 14, connected with the city water system, passes through the upper end of the tank and extends nearly to the bottom of the same. The pipe 14 discharges water into the tank 13 from the street main at city pressure. A feed pipe 15 opens from the bottom of the tank and supplies water by gravity to our improved water heating apparatus.

The feed pipe 15 is connected by an elbow 16 with the pipe 17, and the pipe 17 discharges water into the feed-water receptacle 18, which consists of a flattened tube, shown in longitudinal section in Fig. 1, and in cross section in Fig. 2, having closed ends, which, however, are tapped as seen at 19 and 20 in Fig. 1. The pipe 17 enters the feed-water receptacle 18 through the tap 19. Through the tap 20 of said receptacle 18 extends a pipe 21, which is connected by an elbow 22 with a pipe 23. An elbow 24 connects the pipe 23 with a nipple 25, which is secured in the threaded opening of the cap 2. The inner end of the nipple 25 is connected to the end of a pipe coil 26, which consists of a plurality of parallel pipes, connected by elbows at their contiguous ends, as seen in Fig. 1.

The upper pipe of the coil 26 passes out through the closed end of the cylinder 1, through a tap or nipple there, and is connected by an elbow 27 with the pipe 28, which is connected by an elbow 29 with the pipe 30. The pipe 30 enters the T-shaped union 31 from which a pipe 32 passes through the top of the tank, as shown in Fig. 2. The cylinder 1 has at its top an integral pipe 33, opening from the cylinder near its open end, and also near the tap 3 of the cylinder at its closed end. Through the tap or nipple 5 of the cylinder 1 a pipe 34 extends up and it is provided with an automatic air valve 35.

The apparatus, thus far described, is adapted to heat water from the steam-boiler, hot-water-heater, or hot-air-furnace, constituting the house-heating system.

The water from the tank or reservoir 13 supplies our water-heating apparatus. The water passes through the pipe 15, the elbow 16 and pipe 17, into the receptacle 18, thence through the pipe 21, elbow 22, pipe 23, elbow 24 and nipple 25 into the coil 26. The valves 8 and 11 being open, the steam or hot water or hot air passes through the pipes 7 and 9 into the cylinder 1, and from the cylinder 1 out through the pipes 10 and 12.

While the steam or hot water or hot air is passing through the cylinder, it surrounds the pipe coil 26, which is supported, as shown, near the center of the cylinder and lengthwise thereof, and so heats the pipe-coil and the water which it contains. The water, so heated in the pipe coil, passes through the elbow 27, pipe 28, elbow 29, pipe 30, T-union 31 and pipe 32, into the tank 13. When 10 faucets are opened in one or more rooms of the building, the hot water from the tank 13 passes up through the pipe 32, T-union 31, pipe 36, elbow 37 and pipe 38, leading to such faucet or faucets. As shown in Fig. 3, the 15 pipe 7 connects the valve 8 and pipe 9 with a source of heat 58, which may be a dome or chamber of a steam boiler, water boiler, or hot air furnace.

To adapt our improved water-heating device to heat derived from a gas burner, instead of a house-heating system, we provide a gas burner 39, having a plurality of gas jets 40. A gas pipe 41 conducts gas from the street main, or other source, through the 20 valve 42 and pipe 43 to the gas burner 39. The pipe 9 is tapped, as shown at 44, and a pipe 45 threaded therein. A valve 46 connects the pipe 45 with a pipe 47. The burner 39 conducts cold water from the street main 25 under city pressure. The valve 42 has a lever or handle 48 to operate the same, and a valve 46 has a lever 49 to operate the same. A link 50 is pivoted at one end to the lever 48, and at its opposite end to the lever 49. 30 A pipe 45 is connected to the valve 46 and pipe 9.

A case 51 is made of a casting of composition consisting of asbestos and Portland cement, or other suitable material. This case 40 has an open bottom, four vertical sides and a top, which is semicircular in cross section. One edge of the top of this case is longitudinally enlarged and grooved, as indicated at 52, and one longitudinal edge is inserted into 45 the groove 52 and secured therein by any suitable means. The case 51 is perforated, as shown in Fig. 1 for the passage of the pipes 9, 17, 28 and 34.

To heat water by means of our apparatus, 50 when the heat is to be derived from gas, the valves 8 and 11 must be closed. The water passes, as before described, through the pipes 15 and 28 and the intermediate pipe coil and pipe connections. By operating the handle 55 48, both the water valve 46 and the gas valve 42 are turned. Cold water passes through the pipes 47, 45 and 9 into the cylinder 1 and fills the same. The gas is ignited at the jets 40. As the feed-water receptacle 18 is immediately above the gas jets 40 and is a flattened tube having a comparatively large horizontal area on its under side, exposed to the direct flames of the gas jets 40, the water 60 passing through it is subjected to intense heat. The heat of these gas flames also fills

the interior of the case 51, and quickly heats the entire exterior surface of the cylinder 1, and the water contained in the cylinder 1 is raised to a high temperature. As the water 70 introduced directly from the street mains) a circulation is set up therein, as soon as the gas jets 40 are lighted.

The water in the cylinder 1 which is the most heated rises and flows through the pipe 75 33, as indicated by the arrow 53, and is discharged therefrom into the cylinder 1 near the inner end of the pipe 9. Thus the water in the receptacle 18 is heated by the direct action of the burning gas jets and thence 80 flows up through the pipe coil 26 and out through the pipe 28 to the tank 13, and at the same time the water while passing through the pipe coil 26 is brought to a still higher temperature by the heated water 85 within the cylinder 1 in contact with the exterior surfaces of said pipe coil throughout its entire extent. When the gas valve 42 is closed by turning the lever or handle 48, the link 50, by moving the lever 49, causes the water valve 46 to close, thereby shutting off the water from the street main. The water may be discharged from the cylinder 1, when 90 convenient, by opening the valve 11, the air valve 35 facilitating such discharge. 95

In Figs. 4 and 5 we show an improved water-heating apparatus provided with means of electric heating. In said figures 54 represents an electro-magnetic coil, having a core 55, passing through it. The coil 54 is supported beneath the cylinder 1 by the core 55, the two poles or ends of the latter extending up vertically into the cylinder 1. On the upper ends or poles of the core, respectively, are the radiating plates 56. The electric switch board is shown at 57 and wires 58 connect the coil 54 with a source of electricity. To heat water in our improved apparatus by means of electricity, the valves 8 and 11 are closed and the valve 46 is opened. Water 100 flows from the street main through the pipes 47, 45, and fills the cylinder 1, as shown in Fig. 5. By operating the switch 57, electricity is turned on and energizes the electro-magnetic coil 54 and the core 55, and the radiating plates 56 are thus heated. As the plates 56 are surrounded by water in the cylinder 1, as represented in Fig. 5, the water is heated from said plates, and the water in the coil 26, which enters through the pipes 15, 17, and is discharged through the pipe 28, receives its heat from the water outside the coil in the cylinder 1. 115

By means of this improved apparatus it is possible, during the winter to supply the house with hot water heated from the steam-boiler, hot-water-heater, or hot-air-furnace of the usual house-heating system, and in summer to supply water heated by a gas burner or by an electric coil. 120 125 130

We claim as a novel and useful invention and desire to secure by Letters-Patent:—

1. In a water heating system, the combination of a cylinder having an outlet pipe and a valve therein, a feed pipe entering said cylinder to conduct water thereto from a street main, a pipe coil in the cylinder, a hot-water tank, a feed pipe from the tank to said coil having a portion thereof horizontally flattened, a return pipe from the coil to the tank, a gas pipe, a burner on the gas pipe in proximity with the flattened portion of the second named feed pipe, and a case over said cylinder to conduct the heat of said burner 15 to the exterior surfaces of the cylinder.
2. In an apparatus of the class described, the combination of a cylinder having an outlet pipe and a valve therein, a feed pipe entering said cylinder to conduct cold water thereto, a pipe coil in the cylinder, a hot-water tank, a feed pipe from the tank to the coil, a return pipe from the coil to the tank, a gas pipe, a case inclosing said cylinder, and a burner on the gas pipe within said case but 20 beneath the cylinder and in proximity with the last named feed pipe.
3. In an apparatus of the class described, the combination of a cylinder; an inlet pipe entering said cylinder; an outlet pipe from 25 said cylinder; a valve in each of said pipes; a pipe coil supported in the cylinder; a tank; a horizontally flattened receptacle; a feed pipe adapted to conduct water from the tank to said receptacle; a feed pipe adapted 30 to conduct water from the said receptacle to the pipe coil; a pipe adapted to conduct water from the pipe coil to the tank; a pipe adapted to conduct cold water from a street main under pressure into the cylinder; a valve 35 in the last named pipe; a case or hood having an open bottom and extending over the cylinder to inclose the same; a gas pipe; and a burner upon the gas pipe in proximity 40 to said receptacle, but near the open bottom 45 of said case or hood.
4. In an apparatus of the class described, the combination of a cylinder; an outlet pipe for the cylinder; an outlet pipe from the cylinder; a valve in each of said pipes; a pipe coil supported in the cylinder; a tank; a horizontally flattened receptacle; a feed pipe adapted to conduct water from the tank to said receptacle; a feed pipe adapted to conduct water from said receptacle to the pipe coil; a pipe adapted to conduct water from the pipe coil to the tank; a pipe adapted to conduct cold water under pressure from a street main into the cylinder; a valve in the last named pipe; a case or hood having an open bottom and extending over the cylinder to inclose the same; a gas pipe; a burner on the gas pipe in proximity with said flattened receptacle, but near the bottom of the hood or case; a valve in the gas pipe having a handle; a handle on the valve of the cold water pipe from the street main; and a link pivoted at its ends to said handles, respectively, and adapted to operate said two last named valves in unison.
5. In an apparatus of the class described, the combination of a cylinder; a pipe adapted to conduct cold water from a street main with said cylinder; a tank; a pipe coil supported in the cylinder; a feed pipe adapted to conduct water from the tank to the pipe coil; a pipe adapted to conduct water from the pipe coil to the tank; an electro-magnetic-coil supported beneath the cylinder, and said coil having its two poles extending into the latter, and a case or hood having an open bottom and extending over the cylinder.

In testimony whereof we affix our signatures in presence of two witnesses.

FRANK DUPUIS.
